US0D1108305S

(12) **United States Design Patent** (10) **Patent No.:** **US D1,108,305 S**
(45) **Date of Patent:** **** Jan. 6, 2026**

(54) **UNMANNED AERIAL VEHICLE**

(71) Applicant: **Guangzhou Walkera Technology Co., Ltd.**, Guangzhou (CN)

(72) Inventors: **Tom Luo**, Guangzhou (CN); **Peter Luo**, Guangzhou (CN)

(73) Assignee: **GUANGZHOU WALKERA TECHNOLOGY CO., LTD.**, Guangzhou (CN)

(**) Term: **15 Years**

(21) Appl. No.: **29/911,228**

(22) Filed: **Aug. 30, 2023**

(51) **LOC (15) Cl.** **12-06**

(52) **U.S. Cl.**

USPC **D12/16.1**

(58) **Field of Classification Search**

USPC D12/16.1, 328, 326, 344, 345, 1–4, 174, D12/319–325, 327, 329–343; D21/301, D21/436, 441, 443, 444, 446, 447, 448, D21/449, 450, 451, 452, 453

(57) **CLAIM**

The ornamental design for an unmanned aerial vehicle as shown and described.

DESCRIPTION

FIG. 1 is a front elevational view of an unmanned aerial vehicle showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a perspective view of the unmanned aerial vehicle in a folded state; and,

FIG. 10 is a perspective view of the unmanned aerial vehicle in use.

The broken lines illustrate portions of the unmanned aerial vehicle which form no part of the claimed design.

1 Claim, 10 Drawing Sheets
